US00D491826S1

(12) **United States Design Patent** (10) Patent No.: **US D491,826 S**
Shaland et al. (45) Date of Patent: ** Jun. 22, 2004

(54) **REFLECTOR**

(75) Inventors: **Alexander Shaland**, Lyndhurst, OH (US); **Douglas F. Kreysar**, Duvall, WA (US); **Chan Ho Ming**, Kowloon (HK)

(73) Assignee: **Actron Manufacturing Company**, Cleveland, OH (US)

(**) Term: **14 Years**

(21) Appl. No.: **29/181,437**

(22) Filed: **May 9, 2003**

Related U.S. Application Data

(63) Continuation of application No. 29/154,186, filed on Jan. 17, 2002, now abandoned.

(51) **LOC (7) Cl.** **10-05**

(52) **U.S. Cl.** **D10/111**

(58) **Field of Search** D10/111; 362/3-18, 362/372, 283, 284, 346, 223, 256, 277,

(57) **CLAIM**

We claim the ornamental design for a reflector, as shown and described.

DESCRIPTION

FIG. 1 is a bottom right rear isometric view of a timing light reflector showing our new design, the top right front isometric view (not shown) being a mirror image thereof:

FIG. 2 is a rear elevational view thereof:

FIG. 3 is a bottom plan view thereof:

FIG. 4 is a left side elevational view thereof, the right side elevational view (not shown) being a mirror image thereof;

FIG. 5 is a top plan view thereof; and,

FIG. 6 is a front elevational view thereof.

1 Claim, 3 Drawing Sheets
